QUICK DETACHABLE HANDLE FOR TOOLS

Filed July 1, 1931

UNITED STATES PATENT OFFICE

CHARLES SCHEUNER, OF CHICAGO, ILLINOIS

QUICK DETACHABLE HANDLE FOR TOOLS

Application filed July 1, 1931. Serial No. 548,241.

The invention has relation to detachable handles for tools, having for an object to provide certain improvements therein including a self contained handle wherein there are 5 no detachable parts to become lost or mislaid. Other objects and advantages will hereinafter appear.

The invention consists in the novel construction and combinations of parts as set 10 forth in the appended claims.

In the accompanying drawings illustrating the invention:

Figure 1 is a central longitudinal section of the invention on the line 1—1, Fig. 2.

15 Figure 2 is a side view of the invention.

Figure 3 is a view similar to Figure 1 with the tool released and ready for withdrawal from the handle.

In these drawings, the numeral 1 designates the body of the handle which is longitudinally channeled at 2 to receive a longitudinally movable spring strip 3.

At one end this spring strip is provided with spring jaws 4, 4, opposed to each other, 25 the inner ends of said jaws being brazed or otherwise forming part of the spring strip at 5, and being normally received within a recess or channel enlargement 6, of one end of said handle, in such manner that the outer 30 ends of the lateral walls of said recess bear against the inner ends of said spring jaws to maintain said jaws closed together, the closing of the jaws together being brought about during the longitudinal movement of 35 the spring strip 3 in one direction through engagement of the lateral walls of said recess with said spring jaws.

In the longitudinal movement of the spring strip 3 in the opposite direction, the spring jaws 4, 4, are moved without said recess 6, and spring apart as shown in Figure 3.

The knife, file, or other tool 7, is provided with perforations 8 in its tang 9, said tang being received between said spring jaws 4, 4, 45 in which position, its said perforations are engaged by pins 10, of one of said jaws 4, said pins being long enough to extend past the perforations of said tang into engagement with aligned perforations 8' of the opposed 50 jaw. The spring jaws 4, 4, are spaced apart

and between and located at the root of the jaws is the squared end 19 of the strip 3. In placing the tool in position between the jaws, the squared end 20 of the tool tang abuts against the squared end 19 of said strip to 55 position the perforations 8 of the tang relative to the perforations 8' and pins 10 of the jaws, so that when the jaws are closed towards each other said pins will accurately engage said perforations. This squared end 60 engagement of the parts also braces the tool against strain.

In the movement of the strip 3 in one direction, the inner ends of the spring jaws 4, 4, which in spread or open position are located 65 without the recess or channel enlargement 6 of the handle, as shown in Figure 3, are brought closely within the same, as in Figure 1, and the inner of the perforations 8, 8', of one jaw and of the tool tang and the inner of 70 the pins 10 engaging said perforations are also brought within said recess, being covered and protected by the side walls of said recess to thereby hold said pins securely engaged with said perforations and to brace 75 the tool against strain. The tool is provided with squared transverse shoulders 21 and the spring jaws have squared free ends 22, engaging said shoulders in closed position of 80 said jaws to further brace the tool against strain.

Thus, when the spring strip 3 is moved in one direction, the opposed jaws 4, 4, spring apart, and release said tang, inasmuch as the pins 10 of one of the jaws will be brought out 85 of engagement with the perforations 8' of the other jaw and with the tang perforations 8. In order that this release may be facilitated, the pins 10 are beveled at their outer ends at 11.

In the movement of the spring strip 3 to close the jaws 4, 4, together to grip the tang, at the end of the movement, a lateral pin or catch 12 of the other end of said strip is engaged with the outer extremity 13 of one side 95 of the handle 1, to hold the jaws 4, 4, closed together, the inherent elasticity of the spring strip holding said catch engagement.

In releasing the tool, the lower end of the spring strip 3 is moved laterally, to move the 100

catch 12 from the handle end 13, after which the spring strip 3 is moved longitudinally of the channeled handle to release the jaws 4, 4, as stated, a loop 14 at said lower end of the spring strip 3 during this longitudinal movement of the strip, entering a recess 15 of the other end of the handle. The longitudinal movement of the spring strip to close the jaws 4, 4, together is limited by engagement of lateral squared shoulders 4', 4', of lateral extensions of said jaws against the adjacent squared end of the handle, as shown in Figure 2. This squared engagement of the parts further braces the tool against strain. As shown, the recess 15 is formed by bending one side of the lower end portion of the handle 1 outwardly as at 16.

In practice, the pins 10 have each a reduced threaded stem 17, engaging the perforation of the related jaw 4, a nut 18, being threaded upon said stem and seated in a lateral recess of said jaw.

I claim:—

1. In a detachable handle for tools, where-
25 in the tool tang is provided with a perfora-
tion, and the tool handle has a longitudinal
channel, and a longitudinal strip has sliding
engagement with said channel and is pro-
vided at one end thereof with opposed spring
30 jaws one of which has a perforation and other
of which is provided with a pin engaging the
perforations of said tang and of the first
named jaw; said jaws having the inner end
35 portions and the perforation and the pin
thereof located closely within and covered
and protected by the side walls of said chan-
nel to hold said pin securely engaged with
said perforations and to brace the tool against
strain.
- 40 2. In a detachable handle for tools, where-
in the tool tang is provided with a perfora-
tion, and the tool handle has a longitudinal
channel, and a longitudinal strip has sliding
engagement with said channel and is provid-
45 ed at one end with opposed spring jaws one of
which has a perforation and the other of
which is provided with a pin engaging the
perforations of said tang and of the first
named jaw; said jaws having the inner end
50 portions and the perforation and the pin
thereof located closely within and covered
and protected by the side walls of said chan-
nel, and said strip having a squared end lo-
cated at the root of and between said jaws
55 and the tool tang having a squared free end
engaging said strip end to accurately position
the tang perforation relative to the pin and
jaw perforation prior to engagement.
- 60 3. In a detachable handle for tools, where-
in the tool tang is provided with a perfora-
tion, and the tool handle has a longitudinal
channel, and a longitudinal strip has sliding
engagement with said channel and is provid-
65 ed at one end thereof with opposed spring
jaws one of which has a perforation and the

other of which has a pin engaging the perforations of said tang and of the first named jaw; said jaws having the inner end portions and the perforation and the pin thereof located closely within and covered and protect-
70 ed by the side walls of said channel, and said strip having a squared end located at the root of and between said jaws and the tool tang having a squared free end portion engaging said strip end, said jaws having squared free ends and said tang having squared transverse shoulders engaged thereby to brace the tool against strain.

In testimony whereof I affix my signature.

CHARLES SCHEUNER.
